(57) **CLAIM**

The ornamental design for a motorcycle frame cover plate, as shown and described.

DESCRIPTION

FIG. 1 is a front perspective view of a motorcycle frame cover plate embodying my new design;

FIG. 2 is a front elevation view thereof;

FIG. 3 is a rear elevation view thereof;

FIG. 4 is a right side elevation view thereof; and,

FIG. 5 is a left side elevation view thereof.

The mounting holes, splined front surface portion and rear surface features shown in broken lines form no part of the claimed design.
